[57] CLAIM

The ornamental design for a doll display case, as shown and described.

DESCRIPTION

FIG. 1 is a perspective view of a doll display case showing my design;

FIG. 2 is a front elevational view thereof;

FIG. 3 is a back elevational view thereof;

FIG. 4 is a right side elevational view thereof, the left side view being a mirror image of the right side;

FIG. 5 is a top plan view thereof; and,

FIG. 6 is a bottom plan view thereof.

The broken line representation of a doll in FIG. 1 is for illustrative purposes only and forms no part of the claimed design.
